(57) **CLAIM**

The ornamental design for a headlamp, as shown and described.

DESCRIPTION

FIG. 1 is a front, top and right-side perspective view of the headlamp showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is a rear, bottom and left-side perspective view thereof;

FIG. 9 is an enlarged view, of circled portion 9, of FIG. 1, thereof; and,

FIG. 10 is an alternate configuration in another perspective view thereof.

The broken lines throughout the drawing figures depict portions of the headlamp that form no part of the claimed design.

The dot-dash broken lines depict the boundaries of the FIGS. 1, 8, 9 and 10 enlargement that forms no part of the claimed design.

1 Claim, 10 Drawing Sheets
